UNITED STATES PATENT OFFICE.

BARTON H. JENKS AND WM. A. TUTTLE, OF PHILADELPHIA, PA.

IMPROVEMENT IN COTTON-GINS.

Specification forming part of Letters Patent No. 26,681, dated January 3, 1860.

To all whom it may concern:

Be it known that we, BARTON H. JENKS and WILLIAM A. TUTTLE, of the city and county of Philadelphia, and State of Pennsylvania, have made a new and useful Improvement in Cotton-Gins; and we do hereby declare the following to be a full, clear, and exact description of the same, reference being had to the annexed drawings, making a part of this specification, in which—

Figure 1 is a longitudinal section showing the ginning cylinder and brush. Fig. 2 is an end view, with the door removed.

Our improvement consists in surrounding a portion of the ginning-cylinder with smooth metallic bands or ribs, so placed as to be concentric, or nearly so, with their outer surface, and just above the line of the points of the gin-roller. These bands or ribs are shown at A A A A, &c. They are placed about one-half inch apart, (more or less,) and are from one-thirty second to one-sixteenth of an inch (more or less) in thickness and about one-eighth of an inch (more or less) in width. They are placed over that portion of the ginning-cylinder upon which the cotton is placed, and where the principal portion of the ginning is done, and are concentric, or nearly so, with the circumference. The under side of these bands are immediately upon the extremity of the teeth of the cylinder, or might be placed beneath the surface of the cylinder in concentric groves, provided the upper surface projects, as stated, beyond the extremity of the teeth of the cylinder.

In the drawings, B represents the ginning-roller; c, the brush. The bands are fastened at D by a staple or any other mode to the inclined board E, and at the other end, F, by a screw and nut, or in any other convenient manner.

The operation of this machine is as follows: The cotton to be ginned is thrown in through the opening G, and falls and in part rests upon and is supported by the smooth metallic bands A A A A, &c. These bands support the material in part thrown in, and as gin-teeth revolve the friction created by part of the material resting on these bands and a part carried forward by the gin-teeth causes a ginning operation along the whole length of the rib. The ribs also prevent the trash from being acted upon by the gin-teeth. The seeds fall through the opening H, while the cotton is carried up, and the final ginning is done at K against either a movable revolving doctor, or in any other convenient manner. The advantage of the bands is that the ginning is effected more expeditiously and in a superior manner by reason of the operation being performed over a large portion of the cylinder, instead of exclusively at the point K, and the trash is not taken up and mixed with the staple.

The size and relative position of the metallic bands might be varied without affecting the operation of the machine.

Having thus described our improvement, what we claim as our invention, and desire to secure by Letters Patent, is—

The arrangement of stationary metallic bands A A A A, &c., arranged concentric with and around either the whole or a part of the circumference of the gin-cylinder and just above the end of the gin-teeth, in the manner and for the purpose herein specified.

BARTON H. JENKS.
WM. A. TUTTLE.
